FILM TRIMMING AND GLUING APPARATUS

Alexander Suter, Teufenthal, Switzerland, assignor to the firm Injecta Aktiengesellschaft, Teufenthal, Aargau, Switzerland

Application December 31, 1937, Serial No. 182,925
In Switzerland January 9, 1937

3 Claims. (Cl. 154—42)

The present invention relates to a film trimming and gluing apparatus of the kind as shown and described in the Swiss Patent No. 164,226, said apparatus having two swingingly arranged clamps for holding the film ends to be trimmed and glued and having also a double sided cutter, a rasp and a pressure block all hinged to the same base plate carrying said clamps.

Hitherto a separate apparatus was needed for each particular width of film, while the apparatus of the present invention can be used for any width of film which is now in use.

The invention, therefore, consists of an apparatus having clamps provided with two rows of tacks on the lower jaw, permitting the films to be fixed to said tacks so as to bring their perforations into the correct continuous sequence when being glued.

As an example, an embodiment of an apparatus according to the invention is shown in the accompanying drawing.

Fig. 1 is a plan view,

Fig. 2 a side elevation, where the position of the movable parts has been changed somewhat and

Fig. 3 a sectional view taken on line III—III of Fig. 1.

Fig. 4 shows a film 16 millimeters wide fixed by the pins,

Fig. 5 shows a film 8 millimeters wide and

Fig. 6 a film 9 millimeters wide fixed by the pins.

In the drawing two swingingly mounted clamps *b* and *c*, facing each other, and adapted to hold the two film ends to be glued are arranged along one edge of a base plate *a*. Clamp *b* is shown in the gluing position, while clamp *c* is shown in the trimming position.

A rasp holder *d* with a rasp *g* and a trimming device with two cutters *e* are arranged on the same axis on the opposite edge of the base-plate. The cutters are arranged in an inclined position to each other which corresponds to the mutual position of the two stationary cutting blades *f*¹ and *f*² fixed to the base plate. Furthermore, cutters and blades are located in such a way that the film ends are cut to such a length that, when swung back into their gluing position, they overlap each other for the purpose of being glued. Previous to such gluing the rasp holder *d* is turned down for a while and the rasp *g* is applied to the film surface to produce the required ruggedness for holding the glue.

Clamps *b* and *c* are each provided with two rows of tacks *h* and *i* some of which, at least, in

the one or the other row, will engage the perforations of any film now in use in order to fix the film ends in the clamps in the correct continuous sequence of perforations when the clamps are brought into gluing position. The form of the perforations in the different kinds of film is not everywhere the same. In the 9 millimeter film the perforations are somewhat longer than in the 16 and 8 millimeter films. Therefore the tack row *h* in clamp *b* (Figs. 1 and 4) intended to fix a 9 millimeter film, shows one tack *h*¹ of an oblong cross section and a number of tacks *h*² of a circular cross section. Tack *h*¹ fits exactly into the perforation of the film and the edge of this latter will touch the upper edge of the clamp, as shown in Fig. 6. The tacks of circular cross section *h*² are staggered transversely in the clamp in order to bear alternately on the lower or upper edge of the perforations. This arrangement permits of an easy fixing and removing of the film.

The first tack *i*¹ of the row *i* has also an oblong cross-section and corresponds to the perforations of the 8 and 16 millimeter films. The other tacks *i*² have a circular cross-section. The reciprocal staggering of these latter tacks is not so great as that of the tacks of the opposite row *h*¹, *h*². The tacks *i*², however, work in quite the same way as the tacks *h*². If a 16 millimeter film, as shown in Fig. 4, is put on the row *i*, *i*² it bears with its upper edge against the inner tacks of the upper row and the film is thus supported on both sides.

The 8 millimeter film, as shown in Fig. 5, is likewise put on the row *i*. It touches the lower edge of the clamp. As proved by experience such a fixing is sufficient for such a narrow film.

The rasp *g* is swingingly held on a rod *g*¹ and is slidably arranged in the clamp *d* in a transverse direction to the film. Its sliding movement is limited by the cross bars *g*³ and *g*⁴. To secure the parallelism and the close contact of rasp *g* with respect to the film end held fast to the face plate *k* screws *g*² are provided shown in Fig. 3. Face plate *k* is likewise held adjustably by an axis *k*¹ permitting of a small pivoting of the plate.

The pressure block *l* in the pressure lid *l*⁰ is likewise held pivotally on a pin *l*¹ and is made adjustable by means of the screws *l*² in order that the film ends to be glued may be closely joined.

What I claim as new is:

1. In a film trimming and gluing apparatus of the type having film clamping members and film cutting means, the improvement which comprises oppositely disposed parallel rows of sta-

tionary pins arranged on said clamping members, the pins of one row being spaced midway between the pins of the second row, the pins being so constructed and arranged that said first row of pins will engage the inner end wall of perforations in the film while the pins in the second row engage the outer end wall of adjacent perforations in said film.

2. In a film trimming and gluing apparatus of the type having film clamping members and film cutting means, the improvement which comprises oppositely disposed parallel rows of stationary pins arranged on said clamping members, the pins of one row being spaced midway between the pins of the second row, the pins being so constructed and arranged that said first row of pins will engage the inner end wall of perforations in the film while the pins in the second row engage the outer end wall of adjacent

perforations in said film, and an elongated pin member at one end of said rows adapted to completely fill one of the perforations in said film.

3. In a film trimming and gluing apparatus of the type having film clamping members and film cutting means, the improvement which comprises oppositely disposed parallel rows of stationary pins arranged on said clamping members, each pair of rows including an inner row 10 and an outer row of pins, the pins of the inner row of each pair being spaced midway between the pins of its respective outer row, the pins being so constructed and arranged that the inner row of pins of one pair will engage the inner 15 end wall of perforations in the film while the outer row of pins of the same pair will engage the outer end wall of adjacent perforations in said film.

ALEXANDER SUTER.
